UNITED STATES PATENT OFFICE.

FRANÇOIS P. A. ROUSSEAU AND LÉON A. PITOT, OF PARIS, FRANCE.

RAILWAY-SLEEPER.

1,386,954.

Specification of Letters Patent.

Patented Aug. 9, 1921.

Application filed November 18, 1919. Serial No. 337,771.

To all whom it may concern:

Be it known that we, FRANÇOIS P. A. ROUSSEAU and LÉON A. PITOT, citizens of the French Republic, residing at Paris, Department of the Seine, in France, and whose post-office address is 7 Rue Scribe, in the said city, have invented certain new and useful Improvements in Railway-Sleepers; and we do hereby declare the following to be a full, clear, and exact description of the invention, such as will enable others skilled in the art to which it appertains to make and use the same.

The present invention consists of a means permitting of increasing the amount of the load on railway tracks by fitting the sleepers within metal members forming non-deformable frameworks.

The metal members, employed such as sleepers, tie beams or sleeves, are of rolled section or cast and are formed at one or more points on their vertical sides with openings bounded by angle members formed from portions thereof which are cut and then bent which angles serve for connecting the wooden and iron members. The connection may be effected by coach screws or bolts.

The incisions to form the angle members may be made during the rolling process, that is to say, when the length has been obtained and cut off, the slight cohesion of the hot metal more easily allowing the cutting operation mechanically.

In the accompanying drawings illustrating the invention Figures 1, 2, 6 and 7 are perspective views of various forms of the invention. Figs. 3, 4, 5 and 8 are perspective views of different modified forms of sleeve members and Fig. 9 a perspective view of a track built up with sleeve members.

Fig. 1. shows a framework of a track for double headed rails supported on chairs. As shown, the framework comprises two metal sleepers 1—1 of rectangular open section which are strengthened by two wooden ties 2 and 3. For economical reasons each of these ties may be formed of two pieces of wood instead of one piece. Fig. 2 indicates a framework for a track for flat bottomed rails formed by two metal ties 4 and 5 of closed rectangular section connected by two wooden sleepers 6 and 7 each formed of two pieces of wood. The metal ties 4 and 5 are arranged at an angle to the wooden sleepers so as to form a surface giving to the rail

bottom an inclination of 1 in 20 toward the inside of the track, as shown at 4^a and 5^a, Fig. 2. Figs. 6 and 7 are somewhat similar to the construction illustrated in Fig. 1 except for the specific construction of the metallic sleepers 1'—1', Fig. 6 in addition showing a framework in which one line of rails is canted relatively to the other line in order to produce a cant in the curved part of the track.

The two frameworks are each formed of two ordinary wooden ties 2' and 3' joined by two metal sleepers 1'—1', each of the wooden ties being formed on economical grounds of two pieces. Fig. 9 shows the arrangement of a switch approach or crossing formed by parallel wooden members arranged normal to the bisector of the angle of crossing so that it can be assembled with two sets of longitudinal sleepers with metal sleeves 8. The sleeves may be formed of shaped members such as those indicated in Figs. 3, 4, 5, and 8 or of members having any other shapes capable of giving the same result. In Fig. 9 each of the longitudinal sleepers 9 may be formed of two pieces of small section, as in Figs. 1 and 2 and 6 and 7.

In all of the modifications shown, the oppositely disposed vertical sides of the hollow metallic members of the framework, whether it be the tie or the sleeper, are cut out at properly spaced intervals to provide outwardly bent angles or securing plates 10, which at the same time provide an opening directly through the metallic member for the insertion of the co-operating wooden tie or sleeper, according to the construction used. It is to be here noted that the tie may be made of metal and cut out as described for the reception of the parallel longitudinal sleepers, as illustrated in Fig. 2, or the sleeper may be made of metal properly cut out in the manner described to receive the wooden tie, as shown in Figs. 1, 6 and 7, the two constructions being interchangeable as desired.

In the case of a switch approach or a frog junction, where there is a gradual change of angle between the sleepers and the ties, the metallic sleepers 8, as shown in Figs. 3, 4, 5, 8 and 9, have been devised. The same principle of assembly, however, is employed in this construction as in the construction illustrated in Figs. 1, 2, 6 and 7, the metallic members being secured in the inter-

connected wooden members by fastenings through the angles or connecting plates 10.

As compared with a track formed of independent sleepers a track formed by two connected sleepers gives a supporting surface 3 or 4 times the amount according to the distance between the sleepers, since the pressure per square centimeter on the ground will diminish proportionately and the resistance 10 to the forces developed by a moving train will increase also in the same proportions.

The application to the rail joints of a non-deformable framework will no longer give rise to apprehension as to displacement of 15 the rails which quickly takes place with independent sleepers due to shocks. The framework will resist the pressure received as also the live weight of a train of which all the elements form a single mass when 20 traveling over heavy and long gradients. They will not require to be tamped and spreading of the gage will not be caused.

A track constructed entirely of such elements will be non-deformable and in consequence the expenses of upkeep will be very much reduced as will also the work required on the track. It will be able to stand very high speeds while offering a maximum of safety.

30 Claims—

1. A railway track support or cross-tie

construction, comprising spaced tubular metallic members and spaced transverse cross-members inserted through and interlocking with said tubular metallic members.

35

2. A railway track support or cross-tie construction, comprising spaced hollow metallic members, oppositely disposed spaced cut out openings in the vertical sides of said hollow members and spaced transverse cross-members inserted through and interlocking with said hollow metallic members.

40

3. A railway track support or cross-tie construction, comprising spaced hollow metallic members, oppositely disposed spaced 45 cut out openings in the vertical sides of said hollow members, outwardly extending angles or connecting plates formed by the cutting out of the sides of said hollow members, and spaced transverse cross-members 50 inserted through and interlocking with said hollow metallic members, said connecting plates providing additional means for securing said interlocking members together.

In testimony whereof we affix our signatures, in presence of two witnesses.

FRANÇOIS P. A. ROUSSEAU.

LEON A. PITOT.
